DESIGN FOR A BUTTON

Charles H. Frank, New Rochelle, N. Y., assignor to Button Rim Corporation, New York, N. Y., a corporation of New York

Application March 12, 1943, Serial No. 109,745

Term of patent 3½ years

To all whom it may concern:

Be it known that I, Charles H. Frank, a citizen of the United States, residing in the city of New Rochelle, county of Westchester, State of New York, have invented a new, original, and ornamental Design for a Button, of which the following is a specification, reference being had to the accompanying drawing, forming a part hereof, in which:

Fig. 1 is a top plan view of a button showing my new design;

Fig. 2 is a side elevational view thereof; and

Fig. 3 is a cross-sectional view taken on line 3—3 of Fig. 1 for the purpose of fully illustrating the configuration of the body of the button.

I claim:

The ornamental design for a button, as shown.

CHARLES H. FRANK.
